MAURICE J. WOHL, OF NEW YORK, AND ABBOT AUGUSTUS LOW, OF HORSESHOE, NEW YORK; SAID WOHL ASSIGNOR TO SAID LOW.

FUEL-HEATER.

1,005,395.

Specification of Letters Patent. Patented Oct. 10, 1911.

Application filed October 17, 1907. Serial No. 397,913.

To all whom it may concern:

Be it known that we, MAURICE J. WOHL and ABBOT A. Low, citizens of the United States, residing in the city of New York, 5 borough of Manhattan, county of New York, and State of New York, and Horseshoe, county of St. Lawrence, and State of New York, have invented a certain new and useful Fuel-Heater, of which the following is a 10 specification.

This invention embodies means for heating a liquid combustible prior to its admission into a vaporizer or carburetor usually associated with internal combustion engines, 15 although it should be understood that the invention may be employed for heating other fluids, and that it may be used in other arts than explosive engines.

The invention is susceptible of embodiment in various forms of mechanical and electrical constructions, but, stated generally, 20 it embodies a metallic pipe, adapted to permit the flow of a liquid therethrough, said pipe being bent for increasing the area of contact for the combustible liquid adapted 25 to flow therethrough, an electrical resistance (one or more) occupying such relation to the conduit as to heat the liquid therein, and means whereby an electric current is supplied to said resistance.

In a practical form of the heater, a bent fluid carrying pipe lies between two electrical heater elements, the latter comprising windings of metallic wire or ribbon coiled 30 on insulated cores, said heater elements being insulated electrically from metallic contact with the said pipe and, also, from clamping members. These members are composed, preferably, of metallic plates 35 which are operated by screws, or their equivalents, for clamping the heater elements into close mechanical engagement with the interposed pipe, for the purpose of heating the latter by the heat developed in the windings 40 on the passage of an electric current through the same.

In the accompanying drawings, we have illustrated a practical embodiment of the invention, but the construction shown there- 50 in is to be understood as illustrative, only, and not as defining the limits of the invention.

Figure 1 is a longitudinal section, partly in elevation, of the new liquid fuel heater in 55 coöperative relation to a vaporizer or car-

buretor of an internal combustion engine. Figs. 2 and 3 are, respectively, a side view and a horizontal section of the liquid heater, the plane of section in Fig. 3 being indicated by the dotted line 3—3 of Fig. 2.

The heater is adapted to be connected with a vaporizer, D, by a suitable branch pipe, d, whereas the pipe, A', is supplied with liquid from a pump, tank, or other source (not shown). It is evident, however, that the 60 electrically heated device may be used in connection with other structures than carburetors. As shown in Fig. 1, the carburetor, D, consists of an elbow, d', adapted to be fastened to the head, E, of an engine 65 cylinder, said head having an intake port, e, which is closed normally by a valve, E', the stem, e', of said valve being operated by a lever, F. The elbow of the carburetor is 70 shown as having an air inlet port, g, the area of which may be regulated by the adjustment of the valve, G. The carburetor is mounted on the cylinder head to be heated by the heat developed in the engine during 75 its operation, but for the purpose of initially heating the carburetor when starting the engine, we have shown said carburetor as being provided with electrically operated 80 heating appliances, G', the latter forming no part of the present invention.

The form of liquid heater illustrated in the drawings embodies a pipe, A', which is doubled or bent into the approximately S-shape illustrated more particularly in Fig. 3. Said bent or doubled pipe, A', is confined between two electrically operated heating elements, H, H', each heating element consisting of a core h, and a winding, h', the latter being composed of a metallic wire or ribbon which is coiled on the insulated core, h. The heater elements, H, H', are applied to the top and bottom faces of the doubled pipe, A', and between the resistance windings, h', of the two heater elements and the doubled pipe there are interposed layers, h², h², of insulating material. The doubled pipe and the heater elements, H, H', are held mechanically in close contact by clamping plates, I, I', but these clamping plates are insulated electrically 90 from the resistance coils or windings, h', by layers, h³, of insulating material. The clamping members, I, I', are metallic plates which are drawn toward each other by suitable bolts or screws, i, whereby the plates 95

or members draw the heater elements, H, H', into close contact with the doubled metallic pipe, A'.

It is preferred to employ thin layers of mica as the means for electrically insulating each heater element from the metallic pipe and the clamping plate, for the reason that the mica layers operate effectually in electrically insulating the winding, h', from the metallic parts while, at the same time, said layers permit the free transmission of heat from the resistance winding to the doubled metallic pipe. If desired, the heater shown in Figs. 3 and 4 may be incased within a suitable jacket composed of a non-conductor of heat.

Having thus fully described the invention, what we claim as new, and desire to secure by Letters Patent is:

1. In a fuel heater, a fuel pipe adapted to supply a heated combustible liquid, said fuel pipe being bent for increasing the area of

contact for the combustible liquid adapted to flow therethrough, and an electrical resistance coöperating with said bent liquid pipe, whereby the combustible liquid adapted to flow through said bent pipe is heated. 25

2. In a fuel heater, a fuel pipe bent for the purpose of increasing the area of the heating surface for the liquid combustible, 30 electrical resistances applied externally and to the respective faces of said bent pipe, metallic plates engaging with said resistances, and means for clamping the resistance and metal plates in fixed relation to the 35 bent or doubled pipe.

In testimony whereof we have signed our names to this specification in the presence of two subscribing witnesses.

MAURICE J. WOHL.

ABBOT AUGUSTUS LOW.
